United States Patent Office

Des. 199,873
Patented Dec. 22, 1964

199,873

HUMIDIFIER

Jerold R. Peterson, Roselle, Ill., assignor to Sunbeam Corporation, Chicago, Ill., a corporation of Illinois

Filed July 15, 1963, Ser. No. 75,812

Term of patent 14 years

(Cl. D62—4)

Fig. 1.

5. +

Fig. 2.

← A

FIG. 1 is a front perspective view of a humidifier embodying my design;

FIG. 2 is a top plan view thereof;

FIG. 3 is a side elevational view thereof;

FIG. 4 is an enlarged fragmentary sectional view taken along line 4—4 of FIG. 2; and

FIG. 5 is an enlarged fragmentary sectional view taken along line 5—5 of FIG. 1.

I claim:

The ornamental design for a humidifier, as shown.
